US0D1087335S

(12) **United States Design Patent** (10) **Patent No.:** **US D1,087,335 S**
(45) **Date of Patent:** **** Aug. 5, 2025**

(54) **BIOPSY NEEDLE**

(71) Applicant: **Brainlab AG**, Munich (DE)

(72) Inventors: **Andrew Ayala**, Munich (DE);
Christina Bodensteiner, Munich (DE);
Elmar Schlereth, Munich (DE)

(73) Assignee: **Brainlab AG**, Munich (DE)

(**) Term: **15 Years**

(21) Appl. No.: **35/519,353**

(22) Filed: **Nov. 20, 2023**

(80) **Hague Agreement Data**

Int. Filing Date: **Nov. 20, 2023**

Int. Reg. No.: **DM/233569**

Int. Reg. Date: **Nov. 20, 2023**

Int. Reg. Pub. Date: **Dec. 15, 2023**

(30) **Foreign Application Priority Data**

May 31, 2023 (EM) 015023119-0001

May 31, 2023 (EM) 015023119-0002

(57) **CLAIM**

The ornamental design for a biopsy needle as shown and described.

DESCRIPTION

2. Biopsy needle

Fig. 2.1 shows a perspective view of the upper side of a biopsy needle; fig. 2.2 shows a perspective view of the lower side of the biopsy needle; fig. 2.3 shows a top view of the biopsy needle; fig. 2.4 shows a left side view of the biopsy needle; fig. 2.5 shows a right side view of the biopsy needle; fig. 2.6 shows a back view of the biopsy needle; fig. 2.7 shows a front view of the biopsy needle; fig. 2.8 shows a bottom view of the biopsy needle.

The broken lines in the drawings illustrate portions of the biopsy needle and form no part of the claimed design.

1 Claim, 8 Drawing Sheets
